2 SHEETS—SHEET 2.

INVENTOR:

John G. Dietrich

UNITED STATES PATENT OFFICE.

JOHANNES GOTTHILF DIETRICH, OF BERLIN-TEMPELHOF, GERMANY.

TOY SOLDIER.

Application filed January 17, 1921. Serial No. 437,952.

To all whom it may concern:

Be it known that I, JOHANNES GOTTHILF DIETRICH, a citizen of the German Empire, residing at Berlin-Tempelhof, Germany, 5 have invented certain new and useful Improvements in Toy Soldiers (for which I have filed applications in Germany, August 17, 1915, and April 15, 1919; Sweden, June 28, 1920; Norway, July 9, 1920; Holland, 10 July 9, 1920; France, July 30, 1920; Poland, July 3, 1920; England, July 10, 1920; Austria, July 22, 1920; Switzerland, July 10, 1920; Belgium, July 10, 1920; Spain, August 24, 1920; Czecho-Slovakia, July 3, 15 1920), of which the following is a specification.

My invention refers to adjustable dolls made of sheet metal or some other suitable flat material and more especially to dolls 20 which are intended to imitate different positions of exercise and rifle drill in a fairly natural manner. According to the present invention, a great variety of such positions is achieved owing to the rifle forming a 25 separate detachable part of the doll and being provided with a breech-lock button undercut in a rectangular form and designed so as to form a link-pin. By means of the said breech-lock button it is possible 30 to link the rifle to any desired point of a flat member of the doll in a detachable manner. Thus the breech-lock button of the toy corresponds, although on an exaggerated scale, to the same part of a real rifle 35 and at the same time forms the means of connection between the doll and the exchangeable toy rifle.

In the drawings affixed to this specification and forming part thereof different 40 modifications of a device embodying my invention are illustrated by way of example. In the drawings—

Figs. 1 to 14 apply to the first modification,

45 Figs. 1 and 5 to 12 being side elevations of a number of positions of rifle drill,

Figs. 2 and 3 a front elevation and plan view, respectively, without the rifle,

Figs. 4, 13 and 14 are details.

50 Figs. 15 to 27 illustrate a second modification,

Figs. 15 and 16 being side and front elevations, respectively, of the rifle, and

Figs. 17 and 18 showing the middle por-

tion of two forms of the pertinent stamping.

Figs. 19, 21 and 23 represent different positions of rifle drill.

Figs. 20 and 22 are the pertinent front elevations of Figs. 19 and 21.

Figs. 24 to 27 show details.

Referring to the drawings, the doll consists of a trunk or body portion 1 which, through its contour and lines impressed upon it on both sides and through being provided with or without color-print, simultaneously represents the neck, the head and the helmet. It furthermore consists of the arms 2 and 3, of shoulder plates 4, 5 inserted between the trunk and each arm, of 70 the thighs 6, the lower legs and feet 7, of a bar 8 linked to the one foot and provided for the purpose of standing the doll, and finally of the rifle 9 designed as a separate and detachable flat part.

In the first modification the breech-lock button 10 consists of a pin with a mushroom head which projects like a pin and is riveted through the rifle (Figs. 13 and 14). The plane base of the button head of the 80 pin intersects with the longitudinal axis of the pin at right angles and the length of the pin coincides with the gauge of material of the flat member (arm) of the doll. On the arm 2 a recess 11 is provided between the raised thumb 12 and the sleeve and a second one 11^a between the raised thumb and the fingers closed together. The shaft of the breech-lock button is inserted in one of these recesses in such a manner 85 that the rim of the recess serves as the link bearing and the shaft of the breech-lock button as the link journal, whilst the button head undercut rectangularly forms the outer abutment for the arm. After this link connection has been established, the right hand can, for instance, be raised, say, up to the tip of the helmet so that the lower edge of the butt of the rifle can be turned past the rounded part of the shoulder plate 5 which 90 is prevented from rotating and has a heart-shaped contour (Fig. 5, dotted lines).

After rotating the arm 3 together with the rifle downwards, the lower edge 9^a of the butt of the rifle supports itself against the 95 straight part 5^b of the shoulder plate which points forward, the rifle thus fixing itself firmly between the plate 5 and the breech-

lock button 10 (Fig. 5, full lines). In this case a joint is formed between 5^b and 9^a as in the case of a vault, so that even with pressure on the mouth of the rifle the rifle is prevented from being turned downwards.

If a different rifle with a shorter butt be employed, the edge of the butt of the rifle may also be propped against the breast edge 1^a of the trunk (Fig. 7). Also in this case 10 the butt of the rifle can be turned past the top of the chest, when the arm is raised (Fig. 8).

Providing two recesses 11 and 11^a, open on top, in front of the thumb 12 and behind 15 it, allows of choosing between several centers of rotation for the rifle. The rifle may also be linked to any other portion of the arm and may be inserted, for instance, in the rounding 16 forming the transition between 20 the upper and the lower arm (Fig. 6), the position of the rifle permanently remaining on edge owing to the length of the button shaft being equal to the thickness of the member (Fig. 13).

25 In order to bring the rifle into connection with two members, i. e. with the two arms, one member, for instance, the left hand, is provided with a button 13 projecting towards the center of the body and undercut 30 rectangularly in the same manner as on the rifle, the length of the button shaft corresponding to the gauge of material of the sheet rifle 9. The rifle can now be fastened to the right hand by means of its button 35 10 and can be made to support itself on the button 13 provided on the left hand (Figs. 10 and 12), or, on the other hand, the rifle may also be fastened by means of this button 13 alone, as, for instance, for shouldering 40 it (Fig. 9).

Instead of a button 13, a bracket support 15 can be provided in the left hand.

For slinging the rifle, recesses 16^a in which the breech-lock button can be inserted, are 45 likewise provided on the trunk designed with the same gauge of material as the flat arm-member, the said recesses for instance being arranged on the level of the haversack and in the vicinity of the knapsack (Fig. 11).

50 In the second modification (Figs. 15 to 23) the breech-lock button is formed by simply bending off a tongue on the rifle, this tongue consisting of a strip 17 and a head-shaped enlargement 18 or 19 arranged at right angles to it (Figs. 17 and 18). At its base the strip 17 is also deflected at right angles in regard to the sheet part representing the rifle, and the length of the strip again corresponds to the gauge of material 55 of the member 2 or 3 forming the arm. In consequence of the deflection of the strip originally disposed in the plane of the sheet rifle, the breech-lock button projects up to or even beyond the edge of the rifle corresponding to the real original. In the same

manner the button of the left hand is formed by twice bending off the fingers at right angles, the stamping representing the hand with stretched fingers being deflected in two lines 19—19 and 20—20 which run parallel 70 with one another at a distance equal to the gauge of material of the rifle and obliquely in regard to the row of knuckles (Figs. 26 and 27). Owing to the oblique deflection the tips of the fingers form a supporting 75 groove (Figs. 23 and 24) with the thumb part of the hand, which said groove supports the rifle placed against the shoulder as in the case of the living model.

Fig. 21 shows another manner of utilizing the bending of the hand and the breech-lock button provided on the edge of the rifle, at the same time. If a similar deflection is also provided in the right hand, the rifle can be hung on the right arm stretched 85 downwards obliquely, by means of its breech-lock button, the deflection of the right hand securing the rifle against slipping off forwards, whilst the deflection of the left hand can be laid around the barrel of the 90 rifle.

I claim:

1. In a sheet metal doll in combination, a body portion, an arm and hand linked to said body portion, a sheet metal rifle forming a separate part and a breech-lock button on said rifle, the shaft of said button equaling in length the thickness of said arm.

2. In a sheet metal doll in combination, a body portion, an arm and hand linked to said body portion, a sheet metal rifle forming a separate part, a breech-lock button on said rifle, the shaft of said button equaling in length the thickness of said arm and an indenture in said hand forming a bearing 105 for said shaft.

3. In a sheet metal doll in combination, a body portion, an arm and hand linked to said body portion, a sheet metal rifle forming a separate part, a breech-lock button on said rifle, the shaft of said button equaling in length the thickness of said arm and indentures on both sides of the thumb in said hand forming bearings for said shaft.

4. In a sheet metal doll in combination, a body portion, an arm and hand linked to said body portion, a sheet metal rifle forming a separate part, a breech-lock button on said rifle, the shaft of said button equaling in length the thickness of said arm and an indenture in the rear edge of said body portion forming a bearing for said shaft.

5. In a sheet metal doll in combination, a body portion, an arm and hand linked to said body portion, a sheet metal rifle forming a separate part and a breech-lock button on said rifle formed by bending off part of said rifle, the shaft of said button equaling in length the thickness of said arm.

6. In a sheet metal doll in combination, a

- body portion, an arm and hand linked to said body portion, a sheet metal rifle forming a separate part, a breech-lock button on said rifle and the shaft of said button equaling in length the thickness of said arm and said button being undercut rectangularly. 7. In a sheet metal doll in combination, a body portion, an arm and hand linked to said body portion, a sheet metal rifle forming a separate part, a breech-lock button on said rifle, the shaft of said button equaling in length the thickness of said arm and a rectangularly undercut button on the inner side of said arm. 8. In a sheet metal doll in combination, a body portion, an arm and hand linked to said body portion, a sheet metal rifle forming a separate part and a breech-lock button on said rifle, the shaft of said button equaling in length the thickness of said arm, the fingers of said hand being bent inwards so as to form a support for said rifle. 9. In a sheet metal doll in combination, a body portion, an arm and hand linked to said body portion, a sheet metal rifle forming a separate part and a breech-lock button on said rifle, the shaft of said button equaling in length the thickness of said arm, said hand being bent twice substantially at right angles, the bending lines extending obliquely across said fingers and being spaced apart about the thickness of said rifle.

In testimony whereof I affix my signature.

JOHANNES GOTTHILF DIETRICH.
